UNITED STATES PATENT OFFICE.

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN.

TABLE-TOP CONSTRUCTION.

Application filed March 18, 1925. Serial No. 16,303.

This invention relates to table construction and more particularly pertains to the table top construction and has for its object the provision of a composite top in which the 5 major portion is composed of a silencing pad.

The all-metal tables which are now most generally used have several disadvantages in that the enamel which is coated over the metal chips in time and the table surface is 10 readily ruined and can be repaired only by completely enameling the top surface of the table. In addition, these metal table tops are noisy and extreme care must be taken in setting dishes or other fragile articles on 15 the table because if they are dropped down or carelessly placed, they are liable to be broken.

The object of this invention is to provide a table which enables one to set dishes thereon without exercising this extreme care. Another purpose is the provision of a removable pad for the table top so that when the same 20 may be replaced by a new pad at a very little cost, and the table is as good as new. Such a construction is light and yet, due to the reinforcing, it is extremely strong, and will not sag or warp.

In the drawings:

Fig. 1 is a perspective view of a table top construction in accordance with my invention.

Fig. 2 is a section on the line 2—2 of Fig. 1.

Fig. 3 is a cross sectional view through the moulds, showing how the cast stone moulding 30 is cast on the large reinforcing slab.

Fig. 4 is a sectional detail showing the same removed from the mould.

Fig. 5 is a similar section showing the silencing pad fitted therein.

Fig. 6 is a perspective view of a modified form of construction in which the silencing pad is composed of a plurality of sections 40 fitted together.

Fig. 7 is a section on the line 7—7 of Fig. 6.

Fig. 8 is a modified form of construction, showing the cast stone covering the entire surface of the reinforcing slab but recessed to receive the silencing pad.

Fig. 9 is a sectional detail showing how this 50 table top may be assembled to a cast stone depending framework.

Fig. 10 is an enlarged detail section of another modified form of construction, showing a metal pan secured in place in which the 55 silencing pad is fitted.

Fig. 11 is a detail in perspective of the metal pan.

Fig. 12 is a sectional detail showing a further modified construction in which the metal pan is provided with a flange through which 60 a screw may be passed for fastening the pan to the slab.

The table top comprises a fibrous slab *a*, preferably of wood. This slab *a* is floated within a mould *x*, and is so located therein 65 that the same is spaced from the side walls of the mould. A core *b*, which may be removable as here shown, or may be made integral with the mould, abuts against the face of the wood slab and a stone cement is poured 70 in the mould and fills up the space between the slab and the outer mould, thus providing a moulding *c*, which is cast-united to the wood slab. A thin sheet metal plate *d* may be secured to the slab so as to cover the exposed face of the slab which will prevent any moisture which may have leaked past the silencing pad *e* from coming into contact 75 with the wood slab *a*. Fastening devices, such as the nails *e*, shown in the drawings, 80 may be utilized for keying the stone to the wood slab, although it will be obvious that there are other forms of fastening devices which may be used. After the slab with the moulding secured thereto is removed from the 85 mould, the large silencing pad, preferably formed of linoleum, may be fitted in the recess *f*.

This silencing pad of linoleum is preferably the standard heavy linoleum that may 90 be purchased anywhere and is cut so as to exactly fit into the recess *f*.

However, I may use a plastic material which I can fill into the recess *f* and which will harden and solidify when allowed to 95 set for a definite length of time. This material when solidified is practically the same as the sheet linoleum and possesses the same characteristics and gives equally as good results. This material is composed of a mixture of 30% magnesium oxide (dry powder), 15% of wood flour, 10% of ground asbestos fibre, 10% of kieselguhr and 40% of silica, all percentages computed by weight. To this mixture of dry ingredients is added sufficient magnesium chloride in solution at 26 degrees Bé. gravity to reduce the mix to a wet paste suitable for trowelling.

Of course, it is understood that these proportions may be varied and some of the ele-

ments of the mixture may be eliminated entirely or substituted by others and still obtain a pad which serves the purpose.

This table top possesses a large amount of 5 beauty in addition to its great utility, as the cast stone moulding around the edge of the table is an integral or continuous strip and there are no joints which may come apart. They may be cast very smooth with rounded 10 corners and no sharp edges are exposed which may tear the clothes of those coming in contact with it. The major portion of the table top inside of the moulding is provided with the silencing pad which is removable 15 and may be replaced when the same becomes worn or damaged. Preferably this linoleum is secured to the slab by means of some adhesive material such as glue or cement, but this adhesive material merely serves to hold the 20 pad from being easily displaced and does not prevent one from removing the same by applying a little force to break the union between the pad and the slab.

In addition to the form shown in Figs. 1 25 to 5, I may use a pad formed of a plurality of sections *g*, which may be fitted into the recesses *f* in the table top. These pads are made of linoleum or other light material, and are cut very accurately so that they fit very 30 well into the recess and the manufacturer is able to plan any kind of design by using different colored squares of the linoleum. The sheet metal plate *d* here comes into real use 35 as the many joints between the linoleum tile slab *a*.

In Fig. 8 I show the same slab *a*, the same 40 moulding *c* but instead of the sheet metal cover, I show the cast stone as covering the exposed face of the slab, that is,—the stone entirely covers the slab and the four sides or edges, but is recessed as at *h* to receive one or 45 more sections of linoleum which form the sections of the pad. In Fig. 9 the top construction as shown in Fig. 5 is here secured to a cast stone lower and depending framework structure *i*, which is described and 50 claimed in my copending application Serial No. 715,046.

In Figs. 10 and 11, I show a still further modified construction in which the metal pan

k is provided with the side walls *m* and the turned-back flange *n* in which is provided 55 the perforations *o*. This pan may be suitably located in the moulds so that when the stone moulding *c* is cast onto the slab the stone is cast around the turned-back flange *n* and is keyed thereto because of the fact that the 60 stone flows through the perforations *o* in the turned-back flange. This securely anchors the pan to the stone and provides a water- 65 proof pan in which the silencing pad may be set, which prevents any moisture from reaching the wood slab.

One of the purposes of such a pan construction is that when the silencing pad is removed, especially when using a slab 70 formed of one piece, it is necessary to insert a tool about the peripheries of the pad so that the same can be pried up. In inserting this tool between the pad and stone moulding, it is possible that the stone may be chipped 75 especially if the pad does not come out very easily. However, with this metal pan construction, the tool bears against the side walls of the pan and the stone moulding is protected and is not liable to chip when the tool is wedged between the pan and moulding. 80

In Fig. 12 is another modified form of this metal pan in which the pan is provided with the laterally extending flange *p* provided 85 with perforations *r*, through which the screws *s* may be passed and screwing the pan down to the wood slab, which naturally tightly secures this pan to the slab, and when the stone is cast about the slab, it is united to 90 the pan and to the slab and the turned-over flange *n* serves as a metal reinforcement for this moulding which prevents the same from becoming easily broken.

What I claim is:

A table top, comprising a wooden slab provided with a sheet metal protective cover on 95 one face, a moulding of cast stone secured to said slab about the periphery thereof, and a silencing pad laid over the slab inside of said moulding, said sheet metal cover located 100 between the slab and silencing pad and serving to prevent any moisture that might seep past the silencing pad from coming into contact with the wooden slab.

In testimony whereof I have affixed my signature.

LLOYD G. COPEMAN.
